United States Patent

Des. 235,616
Patented July 1, 1975

235,616

ESCUTCHEON

Raymond U. H. Tegner, Lodi, Wis., assignor to
Amerock Corporation, Rockford, Ill.

Filed Dec. 26, 1973, Ser. No. 428,363

Term of patent 14 years

Int. Cl. D8—09

U.S. Cl. D8—179

Fig. 3.

fig. 5.

fig. 6.

fig. 8.

fig. 7.

FIG. 9.

FIG. 10.

FIG. 11.

FIG. 12.

Fig. 13.

Fig. 14.

Fig. 16.

Fig. 15.

FIG. 17.

FIG. 18.

FIG. 19.

FIG. 20.

FIG. 1 is a front view of an escutcheon incorporating my new design in a switch plate.

FIG. 2 is a side view as seen from the right of FIG. 1.

FIG. 3 is an end view as seen from the bottom of FIG. 1.

FIG. 4 is a sectional view taken along the line 4—4 in FIG. 1.

FIG. 5 is a front view of an escutcheon incorporating my new design in a receptacle plate.

FIG. 6 is a side view as seen from the right of FIG. 5.

FIG. 7 is an end view as seen from the bottom of FIG. 5.

FIG. 8 is a sectional view taken along the line 8—8 in FIG. 5.

FIG. 9 is a front view of an escutcheon incorporating my new design in a combined switch and receptacle plate, the side and section being similar to FIGS. 2 and 4 respectively.

FIG. 10 is an end view as seen from the bottom of FIG. 9.

FIG. 11 is a front view of an escutcheon incorporating my new design in a multiple switch plate, the side and section being similar to FIGS. 2 and 4 respectively.

FIG. 12 is an end view as seen from the bottom of FIG. 11.

FIG. 13 is a side view of an escutcheon incorporating my new design in an escutcheon for a knob.

FIG. 14 is a front view of the escutcheon taken along the line 14—14 in FIG. 13.

FIG. 15 is an end view as seen from the bottom of FIG. 14.

FIG. 16 is a sectional view taken along the line 16—16 in FIG. 14.

FIG. 17 is a side view of an escutcheon incorporating my new design in an escutcheon for a deadlock.

FIG. 18 is a front view of the escutcheon taken along the line 18—18 in FIG. 17.

FIG. 19 is an end view as seen from the bottom of FIG. 18.

FIG. 20 is a sectional view taken along the line 20—20 in FIG. 18.

FIG. 21 is a side view of an escutcheon incorporating my new design in an escutcheon for a passage lever.

FIG. 22 is a front view of the escutcheon taken along the line 22—22 in FIG. 21.

FIG. 23 is an end view as seen from the bottom of FIG. 22.

FIG. 24 is a sectional view taken along the line 24—24 in FIG. 22.

The portions shown in broken line are for purposes of illustration only and form no part of my design.

I claim:

The ornamental design for an escutcheon, as shown and described.
